UNITED STATES PATENT OFFICE.

HENRY C. SWAN, OF OSHKOSH, WISCONSIN.

SEAT-LOCK FOR VEHICLES.

SPECIFICATION forming part of Letters Patent No. 538,753, dated May 7, 1895.

Application filed December 29, 1894. Serial No. 533,242. (No model.)

To all whom it may concern:

Be it known that I, HENRY C. SWAN, of Oshkosh, in the county of Winnebago and State of Wisconsin, have invented a new and 5 useful Improvement in Seat-Locks for Vehicles, of which the following is a full, clear, and exact description.

My invention relates to an improvement in seat-locks for holding vehicle seats in place, 10 and is illustrated in the accompanying drawings, in which—

Figure 1 shows the seat-lock in elevation and in locked position. Fig. 2 is a similar view showing the same in unlocked position. 15 Fig. 3 is a vertical section on the line III III of Fig. 1, and Fig. 4 is a vertical section on the line IV IV of Fig. 2.

In the drawings, 2 represents the riser of a vehicle seat to which the lock is attached.

20 3 represents the vehicle body, and 4 is the rail or strip on the body with which the vehicle lock engages.

The lock which is attached to the seat-riser, has a base-plate 5 set against the side of the 25 seat-riser and affixed thereto. Said base-plate has a central hub or boss 6, and an outwardly projecting inclined guide-tongue or bracket 7. The seat-hook 8 is made integral with an oblong cam-yoke 9 which is set around the 30 hub 6, and the shank of the hook has a key-slot through which the inclined guide-tongue or bracket 7 passes, said tongue or bracket being provided with a key-head or enlarged end-portion, which when the hook is elevated 35 to its full extent, by engagement with the sides of the slot, holds the hook to the base-plate.

40 10 is a cam which fits around the hub 6 and within the yoke 9 and which has a face-plate or flange 11 projecting beyond and covering the cam yoke. To guide the hook and to cause it to move vertically when actuated by the cam, as hereinafter described, the base-plate has a vertical guide-slot 12 in which fits 45 a projection 13 on the cam yoke.

14 is a bolt which passes through the hub 6 and holds the parts in place when they are assembled and applied to the seat.

In Figs. 1 and 3 I show a lock applied to 50 the seat and with the parts in the position

which they occupy when the hook 8 has engaged the rail 4 and is drawn up tightly against the rail by manipulation of the cam, thus holding the seat securely to the vehicle body. To unlock the seat, the handle 15 of 55 the cam is turned upwardly into the position shown in Figs. 2 and 4, and by the rotation of the cam within the yoke the yoke and hook are forced downwardly so as to free the hook from the rail 4; but as the hook and cam yoke 60 are moved down, the end of the key-slot engages the inclined guide-tongue or bracket 7, rides thereon, and is moved outwardly beyond the vertical plane of the rail 4, as shown in Fig. 4. The seat may then be raised freely 65 in a perpendicular line without liability of the hook catching on the body-rail. When the seat is again applied to the body and the hook drawn up by the reverse rotation of the cam, the guide-tongue or bracket 7 so guides 70 the shank of the hook as to draw it inwardly and to cause it to engage with the lower edge of the rail, as shown in Figs. 1 and 3.

The advantages of my improved device are that it is entirely automatic in its operation 75 of removing the hooks from the path of the body rail, it is easy to operate, and is simple and durable.

Without limiting myself strictly to the precise construction of parts shown and described herein, since these may be modified by those skilled in the art without variance from my invention as defined in the claims,

What I claim is—

1. A seat-lock having a hook movable longitudinally to and from a holding projection or rail, and also movable with its shank in an outward direction, means by which the hook is so moved longitudinally, and a stationary guide by which the hook and shank are swung 80 outwardly as they move longitudinally away from the holding projection or rail; substantially as described.

2. A seat-lock having a base-plate provided with a stationary outwardly inclined guide-tongue or bracket, a hook having a bearing on said tongue or bracket, and a cam by which the hook is actuated and moved to or from a holding projection or rail, said guide-tongue or bracket operating to cause the hook 90 to 100

to swing outwardly as it is moved away from the rail.

3. A seat-lock having a base-plate, an outwardly inclined guide-tongue or bracket having a key-head thereon, the hook and cam-yoke having a key-slot through which the tongue or bracket passes, and a cam.

4. A seat-lock having a base-plate provided with an outwardly inclined guide-tongue or bracket, a hook having a bearing on said tongue or bracket, and a cam by which the hook is actuated and moved to or from a hold-

ing projection or rail, said guide-tongue or bracket operating to cause the hook to swing outwardly as it is moved away from the rail; said base-plate having a vertical guide-slot in which a projection from the hook fits; substantially as described.

In testimony whereof I have hereunto set my hand.

HENRY C. SWAN.
